(57) **CLAIM**

The ornamental design for a light with solar-cell, as shown and described.

DESCRIPTION

FIG. 1 is a perspective view of a light with solar-cell showing our new design;

FIG. 2 is a front elevation view thereof;

FIG. 3 is a rear elevation view thereof, showing a translucent part with oblique lines;

FIG. 4 is a right side view thereof, showing a translucent part with oblique lines;

FIG. 5 is a left side view thereof;

FIG. 6 is a top plan view thereof;

FIG. 7 is a bottom plan view thereof;

FIG. 8 is a rear perspective view thereof, showing a translucent part with oblique lines and with a cover in an open condition; and,

FIG. 9 is a cross-sectional view taken along line 9—9 of FIG. 2 showing no illustration of the inside mechanism.
